Primary Examiner — Eric L Goodman*Assistant Examiner* — Sarah L Smith(74) *Attorney, Agent, or Firm* — Daryl R. Wright; Greg Carr(57) **CLAIM**

We claim the ornamental design for a model vehicle body assembly, as shown and described.

DESCRIPTION

FIG. 1 is an upper, left, front perspective view of a model vehicle body assembly;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an upper, left, front perspective environmental use view.

In the drawings, the broken line showing of features of a model vehicle body assembly illustrate portions of the model vehicle body assembly that form no part of the claimed design; whereas, the broken line showing of features of the environmental use view depicts environmental subject matter and is provided for the purposes of illustrating environmental use structure and context.
